United States Patent Office.

JAMES M. EVARTS, OF NEW HAVEN, CONNECTICUT.

Letters Patent No. 79,642, dated July 7, 1868.

IMPROVEMENT IN PIPE-TONGS.

The Schedule referred to in these Letters Patent and making part of the same.

TO ALL WHOM IT MAY CONCERN:

Be it known that I, JAMES M. EVARTS, of New Haven, in the county of New Haven, and State of Connecticut, have invented a new and useful Improvement in Pipe-Tongs; and I do hereby declare that the following is a full, clear, and exact description thereof, which will enable others skilled in the art to make and use the same, reference being had to the accompanying drawings, forming part of this specification.

The nature of my invention relates to improvements in adjustable pipe-tongs, the object of which is to provide a more simple and reliable article than those now in use.

It consists in providing a long slot in one of the jaws, where the joint is to be formed with the other jaw, for sliding the pivot, which is fixed to the other jaw, back and forth, which slot, for about half the distance through the jaw, is perpendicular to the face of the jaw, and for the other half, inclined thereto in each direction, so as to present a section of a V-form, or the section of a triangle, of which the base is the longest side. The faces of these said inclined walls of the slot are serrated, and a stud, fitted to the axial pin, and provided with corresponding angular serrated sides, and also with a rectangular portion, to fit into the rectangular portion of the slot, is interposed in the said slot between the jaws, and constitutes the means of securing the jaws at any position with reference to each other, within the range allowed by the said slot, as will be more fully described on reference to the accompanying drawings, wherein—

Figure 1 represents a side elevation of my improved pipe-tongs, and

Figure 2 a section on the line x x of fig. 1.

Similar letters of reference indicate corresponding parts.

A represents the long jaw, provided with the usual hooked nose, and with an elongated slot, B, the walls of which are bevelled on the side to which the short arm C is secured, and serrated on the bevelled portions, as shown in fig. 1. D represents a nut or washer, which is provided with bevelled and serrated sides, to correspond with the sides of the slot, and with a central hole, through which the axial bolt E passes. F represents a thumb-nut, by which the two jaws are held together, and when it is screwed up the face of the jaw C presses it into the slot, so that the projections of its serrated faces mesh into the grooves of the serrations in the bevelled walls of the other jaw, whereby the axial pivot is firmly secured at any point. By loosening the thumb-nut, the nut D may be disconnected from the serrated faces of the slot in the shank A, and moved, as desired, one way or another.

I am aware that the face of one jaw has been heretofore serrated, and a flat serrated washer interposed between the two jaws; but that arrangement necessitates a greater length of the axial bolt, which is objectionable, and the jaws cannot be brought so close together, whereas, in my improved arrangement, the sides of the jaws are brought into contact, and the axial bolt is stronger, in consequence of being shorter.

I am aware of the patent granted to James R. Brown, dated 2d August, 1859, for pipe-tongs, but as his invention differs from mine, I do not wish to claim it; but

What I do claim as new, and desire to secure by Letters Patent, is—

The jaw A, provided with the elongated slot B, having tapered and serrated walls, in combination with the nut D, provided with corresponding inclined and serrated faces, the jaw C, nut F, and the axial pin E, substantially as and for the purpose described.

The above specification of my invention signed by me, this 1st day of April, 1868.

JAMES M. EVARTS.
